John H. Schriber, of New York, N.Y.
Letter Patent No. 1682 Dated Dec. 9th 1853

The schedule referred to in these Letters Patent and making part of the same.

To all whom it may concern:

Be it known that I, John H. Schriber, of the City, County and State of New York, have invented or produced a new and original design for a Mica Lamp Chimney, and I do hereby declare that the following is a full, clear and exact description of the same, reference being had to the accompanying drawings making a part of this specification, in which

Figure, 1, is an elevation of a Mica Lamp Chimney, constructed according to my design.

Figure, 2, a horizontal section of the same, taken in the line x.x, Figure, 1.

Figure, 3, a vertical section of the same taken in the line y.y, Figure, 1.

Des 16082

Similar letters of reference indicate corresponding parts in the several Figures.

A represents the metal base of the chimney, of annular form, the upper part a of which is cylindrical with an evolobead b , extending around it at its center. - The lower part c of the base it is of concave form, it being a section, as shown in Figures 1 and 2. -

B is the body of the chimney, which is of glass. The body B is of cylindrical form at its lower end where it is fitted on the base A, and it is gradually flattened or compressed from the lower end upward forming in its transverse section at all points, a short distance above the base A, an ellipse as will be seen by referring to Figure 2. - This compression of the body B of the chimney is at two opposite points, and the major diameter of the chimney is the same at all points of its height (see Figure 1,) but the minor diameter gradually contracts from the bottom of the body B , upwards (see Figure 3).

C is the metal cap of the chimney the lower part of which is of elliptical form in its horizontal section. - This cap is of taper form, and it may be described as being a hollow cone, the lower part d of which is flattened or compressed at two opposite points, the elliptical form gradually diminishing towards the top e , where the cap assumes a perfect conical form. -

Having thus described my design, what I claim as new and desire to secure by Letters Patent, is,

The general configuration of the parts, as herein shown and described, to form a new and original design for a lamp chimney.
